UNITED STATES PATENT OFFICE.

FORREST W. DIXON, OF CAMBRIDGE, MASSACHUSETTS.

CONVEYING APPARATUS.

Application filed November 10, 1923. Serial No. 673,919.

To all whom it may concern:

Be it known that I, FORREST W. DIXON, a citizen of the United States, and resident of Cambridge, county of Middlesex, and Commonwealth of Massachusetts, have invented an Improvement in Conveying Apparatus, of which the following description, in connection with the accompanying drawings, is a specification, like characters on the drawings representing like parts.

This invention relates to conveying apparatus, and particularly to apparatus of that type designed to convey goods from one or more stations to a given station, such as a packing or shipping room, and also, while so conveying them, to carry them such distance as will provide sufficient time to effect certain results in the condition of the goods, such as drying or hardening them, as in the case of candies, etc.; and the object of the invention is to produce an improved machine for the above purpose having the advantages, among others, hereinafter pointed out.

In the drawings of one embodiment of my invention selected for illustration and description herein,

Fig. 1 is a side elevation of the machine partly broken away for convenience;

Fig. 2, an end elevation from the left, Fig. 1;

Fig. 3, a partial plan of one of the carriers and stabilizers shown and marked 44^e, Fig. 1, looking from the inside of the frame outwardly;

Fig. 4, an end view of that portion of the machine shown in Fig. 3, looking from the left, Fig. 3;

Fig. 5, a similar view of the opposite end of said portion;

Fig. 6, a vertical section from the left on the line 6—6, Fig. 3;

Fig. 7, a vertical section on the line 7—7, Fig. 3, with the stabilizer about to receive a carrier and to proceed to a lower track;

Fig. 8, a similar view with the stabilizer in the opposite position, at the lower track;

Fig. 9, a perspective view of one of the carriers; and

Fig. 10, a partial side elevation of the right hand end of the structure shown in Fig. 1.

Referring first to Figs. 1, 2, my improved apparatus comprises a frame, consisting of a plurality of uprights 1, 2, 3, 4, and similar members, not shown, on the opposite side of

the machine, cross or end members 5, 6, Fig. 2, and others like them, not shown, constituting a support for the apparatus to be described. In Fig. 1 the opposite or right hand end of the frame is broken away for convenience, it being, however, similar in construction to the portion shown in that figure, and shown in Fig. 10.

The particular embodiment illustrated is designed to receive trays of confectionery at a given point, convey it through a plurality of so-called runs in the frame, to give it a suitable time to harden, and then deliver the goods at the end of one of the runs for removal and packing. Hence, the frame is provided, Figs. 2, 10, with the tracks 7, 8, 9, 10, 11, 12, 13, 14, 15, 16, 17, 18, Fig. 1, tracks 20, 22, 24, 26 and similar tracks, not shown, on the opposite side of the machine. It will be noted, Figs. 1, 2, 10, that the tracks 8 and 18 and their mates 7, 17, on the opposite side of the machine, extend the entire length of the frame, and this alone is a convenient construction when it is desired to have the goods left at the end of the lower track; but, if it is desired to have the goods left at the level of the upper track, then it is preferable to have also the intermediate tracks 10 to 16, and 20 to 26 inclusive to extend through only a portion of the length of the frame, and forming in effect two sections or groups, one of which acts to convey the carriers and goods from the top track 8 through various tracks or runs 10, 12, 14 and 16 to the lower track 18, while the other group acts to convey the carriers and goods from the lower track 18 through various intermediate runs 26, 24, 22 and 20 to the point of starting on the upper track 8, as will be described.

The conveyer proper comprises first a carrier or tray carrying member, and second a moving element as a sprocket therefor, the first of which is preferably endless, and may be of any preferred form, herein of the conventional link type, each link 27, Fig. 3, rectangular in shape and having a forwardly curved lip 28 engaging the adjacent link ahead. At frequent intervals, Figs. 1, 9, a link in each chain is provided with a laterally extended pin or post 29 which is received by a socket member 31 on the adjacent end of the carrier.

Power for imparting traveling motion to the conveyer is supplied from any suitable source as a motor 32, Figs. 1, 2, on the frame, on any convenient point, and con-

ected herein by pinion 33 with gear 34 on a shaft with bevel gear 35 in mesh with a similar gear 36 on the shaft 37. This shaft carries at its lower end a worm 38, in mesh 5 with a worm gear 39 on the shaft 40, in the frame.

On each end of the shaft 40, Fig. 2, is also a pinion 41 in mesh with a gear 42 on a shaft 43, of one of the sprockets 44 10 at the end of a run, and carrying the conveyer chain 27, Fig. 6, which shafts, Fig. 3, operate the stabilizers 44^a, 44^b, 44^c, 44^d, 44^e, 44^f and 44^g, between the ends of each 15 pair of runs to stabilize the carrier as it passes from one level to another, and which will be referred to presently.

Each carrier, Fig. 9, comprises, as shown, two end members 45, connected by rods 46, about which the edges of the body 47 of 20 the carrier are curved and secured. On one or both ends, herein one, there is secured to the member 45 and between it and the rods 46, a similar carrier guiding member 48 having the inturned edge or flange 49 25 which engages beneath the flanged track guide 50, Figs. 4, 6, secured to the inner edge near the end of the rails or tracks from which the carriers descend to a lower track, or to which they ascend from a lower 30 track, to guide the tray in a horizontal plane while passing from the track to the stabilizer or vice versa.

It will be observed from Figs. 1, 7, and 35 8. that the ends of each upper track rail of any pair of tracks where the carriers drop from an upper to a lower track and where they ascend from a lower to an upper track is cut off to make clearance for the carriers 40 leaving the upper tracks shorter than the lower tracks, and each short track has also a part of the top and inner flanges of the U-shaped rail cut back still further, see Figs. 45 7 and 8, hence the desirability of the short track guides 50, to ensure proper guidance 45 of the carrier from the track end to the stabilizer or vice versa. These guides on the Fig. 2 right hand ends of the upper tracks of each pair are shown in full lines. On the carrier end also, adjacent the strip 48, 50 is a rib 49^a, the function of which will be described.

It is very desirable that each tray shall be guided or stabilized during its transit from one level to another to guard against 55 its tipping if it has been unevenly loaded, and possible dropping of goods from the carrier to the floor.

Heretofore in machines of similar character, devices have been provided to engage 60 the front and rear corners of the carriers, or bosses or posts thereon to secure stability of the carriers during transit to another level.

The devices have been more or less complicated in construction and action and have

required the addition of many unnecessary parts to the machines with consequent additional requirement of care in maintenance and expense of construction.

I have conceived a novel form of stabilizer 70 for the carriers, simple and inexpensive in construction and positive in action, and which engages the carrier at one point only.

I will now describe my novel stabilizer, selecting, for instance 44^e in the drawing, 75 Fig. 1, of which an inner face view is shown in Figs. 7 and 8, in upper and lower positions respectively; a plan in Fig. 3; rear end, Fig. 4; forward end in Fig. 5, and vertical section in Fig. 6.

Each stabilizer, Figs. 3, 4, comprises an arm 51 extended longitudinally of the machine from a vertical base or bracket 52, adapted to be bolted or otherwise secured to the edge of one of the posts 1, 2, 3. At 80 the opposite end of the arm from the base, Fig. 3, the arm carries a vertical guide member or track 53.

The arm 51, Figs. 4, 5, near the base, carries an upwardly and also a downwardly 90 extended branch arm 54 and 55, respectively, each offset laterally at its ends and with a boss 56 thereon, and to which is secured an arm guide 57.

In the arm 51 is journaled the extended 95 end of one of the shafts 43 carrying one of the sprocket wheels 44, carrying the chain 27, while the outer end, Figs. 3, 4, 6, carries a crank 60, which, in turn, carries at its outer end, Fig. 6, a block 61 having sliding engagement with a ribbed arm 62 by means of a long slot 63 therein, and through which connection, the arm 62 is given a vertically reciprocating movement.

The arm 62, Figs. 3, 4, 6, has, at its free 105 end, a vertically grooved member 64 which engages the guide 57, and it has also at its opposite end an inturned guide engaging flange 65 to engage the guide 53 on the end of the arm 51, Fig. 3, and a carrier end 110 guiding and stabilizing grooved member or box 66 into which the carrier end is directed from the tracks of the runs.

The several parts of the machine are, of course, properly timed and proportioned so 115 that, in operation, as the trays or carriers move, say in the direction of the arrow in Fig. 1, from the right hand end, Fig. 10, toward the left, each carrier, as it reaches the end of its track or run, for instance 120 track 14, Fig. 7, will be directed to a box 66, waiting for it, and into which the rib 49^a on the carrier end will fit sufficiently, snugly to direct the carrier front edge always in a horizontal plane, Fig. 7, and by 125 means of which the carrier will be securely held against either upward or downward tipping movement. There being no element or elements engaging the rear edge of the carrier or rear corner of either end, there 130

is no danger of unequal movement of said carrier engaging elements or an obstruction to either interfering with the orderly and desired transfer of the carrier from one 5 level to another.

In order to permit the carrier to descend with the stabilizer, the track 10, Fig. 7, is cut off a sufficient distance from the stabilizer as already stated, and to guide the carrier 10 horizontally and to ensure its equilibrium while passing from the track end to the stabilizer guide or box 66, the guide 50 for the short track is provided, and it is engaged by the flange 49 on the carrier end. 15 The stabilizer, through the action of the sprocket chain 27, the shaft 43, crank 60, and arm 62 will descend simultaneously with the carrier end in the box, to the level of the track 12 below, Fig. 8, where continued operation of these parts will cause the carrier to travel from the box and to the opposite end of the track where the operation is repeated. 20

In Fig. 1, the stabilizers 44^a, 44^b and 44^c 25 are shown in position for guiding their carriers to the lower of the two tracks, while stabilizers 44^d and 44^e are in position to accompany the carriers from the upper and guide them to the lower of the two tracks. 30

In the right hand, or elevating section of the apparatus generally, Fig. 1, stabilizers 44^f, 44^g, and stabilizers *h*, *i*, *j*, in Fig. 10, are also in position to accompany and guide the carriers to the upper of the two tracks. 35

After traversing the track 20 to its right hand end, Fig. 10, shown, the carriers are of course delivered to the right hand end of the top track 8, the starting point, for removal and packing. 40

At the carrier receiving end of each upper track, the track is also provided with a track guide 50 as shown on track 8, Fig. 1, and track 10, Figs. 7 and 8 at its delivering end, 45 so that the carrier may be properly guided from the stabilizer to the track end which has been shortened to permit the stabilizer to rise with the carrier, the reverse of the action already described.

My invention is not limited to the illustrated embodiment thereof herein described, and I claim:

1. Apparatus of the class described comprising, in combination, an endless conveyer, means to guide it in a series of runs, carriers movably connected to the conveyer in series, each carrier having a guiding member thereon; a carrier track guide also thereon, stabilizers adjacent the end of each run and having a carrier guiding box for the carrier end, and means to move the stabilizer in a substantially vertical and straight line path with sliding engagement of the box by the carrier. 55

2. Apparatus of the class described comprising, in combination, an endless conveyer, 60

tracks of varying lengths to guide it in a series of runs, short track guides for certain of the tracks, carriers movably connected to the conveyer in series, each carrier having a guiding rib thereon, a carrier track guide also thereon to cooperate with the short track guide, stabilizers adjacent the end of each run and having a carrier guiding box for the carrier end, and means to create relative movement between the stabilizer and carrier along a horizontal plane. 70

3. Apparatus of the class described comprising, in combination, an endless conveyer, means to guide it in a series of runs, carriers movably connected to the conveyer in series, each carrier having a guiding element thereon; devices for holding the carriers horizontal during their travel from one run to another, each device comprising a locking box and an upright track in engagement therewith, into which the carrier element slides, and means to reciprocate the box along the track with relative sliding engagement of the same by the carrier, permitting travel of the latter in a curved path. 80

4. Apparatus of the class described comprising, in combination, an endless conveyer, sprockets to guide it in a series of runs, carriers movably connected to the conveyer in series, each carrier having a guiding boss thereon, devices for holding the carriers horizontal during their travel from one run to another, each device comprising a vertically traveling box in engagement with a vertical track and constructed and arranged to travel vertically at a speed corresponding to the rotative movement of the carrier to maintain the latter horizontal. 95

5. Apparatus of the class described comprising, in combination, an endless conveyer, tracks to guide it in a series of runs, short track guides for certain of the tracks, carriers movably connected to the conveyer in series, each carrier having a guiding member thereon, a carrier track guide also thereon; and stabilizers for holding the carriers horizontal during their travel from one run to another, each comprising a vertically moving carrying member for receiving the carrier rib, cranks having sliding engagement with the vertically moving member for operating said stabilizers, and means to operate the cranks in synchronism with the conveyer. 105

6. Apparatus of the class described comprising, in combination, an endless conveyer, means to guide it in a series of runs, carriers movably connected to the conveyer in series, each carrier having a guiding rib thereon; stabilizers for holding the carriers horizontal during their travel from one run to another, each comprising a vertically traveling member with longitudinally sliding engagement with the carrier ribs as the latter progressively reach the stabilizers, 120 125

- and means to operate the same from the conveyer.
7. Apparatus of the class described comprising, in combination, an endless conveyer, means to guide it in a series of runs, carriers movably connected to the conveyer in series, each carrier having a guiding rib thereon; and devices for holding the carriers horizontal during their travel from one run to another, each comprising a pair of parallel motion members for receiving the carrier rib therebetween and means to operate the same from the conveyer.
8. Apparatus of the class described comprising, in combination, an endless conveyer, tracks to guide it in a series of runs, short track guides for certain of the tracks, carriers movably connected to the conveyer in series, each carrier having a guiding boss thereon, a carrier track guide also thereon, to cooperate with the short track guides; and devices for holding the carriers horizontal during their travel from one run to another, each comprising an arm with a sliding block therein and a box member to cooperate with the carrier as it leaves the track, and means including a crank engaging the block to operate the arm in a vertical plane with sliding engagement of the carrier.
9. Apparatus of the class described comprising, in combination, an endless conveyer, means to guide it in a series of runs, carriers movably connected to the conveyer in series, each carrier having a guiding rib thereon; and devices for holding the carriers horizontal during their travel from one run to another, each comprising a two-way vertically moving locking box to hold the carrier against either upward or downward movement while having longitudinally slideable engagement with the carrier end.
10. Apparatus of the class described comprising, in combination, an endless conveyer, means to guide it in a series of runs, carriers movably connected to the conveyer in series, each carrier having a guiding rib thereon, a carrier track guide also thereon; and devices for holding the carriers horizontal during their travel from one run to another, each comprising an arm with a box thereon, and means to move the arm and carrier vertically while in a horizontal position.
11. Apparatus of the class described comprising, in combination, an endless conveyer, means to guide it in a series of runs, carriers movably connected to the conveyer in series, each carrier having a guiding rib thereon; and devices for holding the carriers horizontal during their travel from one run to another, each comprising an arm with a carrier-receiving box thereon and a crank having slideable engagement therewith to move the box vertically.
12. Apparatus of the class described comprising, in combination, an endless conveyer, means to guide it in a series of runs, carriers movably connected to the conveyer in series, each carrier having a guiding rib thereon; and devices for holding the carrier horizontal during their travel from one run to another, each comprising a crank on one of the conveyer members, an arm with a box thereon operated by the crank for receiving one end of the carrier rib, and means to operate the same from the conveyer.
13. Apparatus of the class described comprising, in combination, an endless conveyer, means to guide it in a series of runs, carriers movably connected to the conveyer in series, each carrier having a guiding rib thereon; and devices for holding the carriers horizontal during their travel from one run to another, each comprising a horizontally slotted member moving vertically with a varying degree of engagement with the carrier for guiding one end of the carrier horizontally.
14. Apparatus of the class described comprising, in combination, an endless conveyer, means to guide it in a series of runs, carriers movably connected to the conveyer in series, each carrier having a guiding boss thereon; and devices for guiding the carriers horizontally during their travel from one run to another, each comprising a box for receiving one end of the carrier boss and means to operate the same while the carrier is having reciprocating movement relative thereto.
15. Apparatus of the class described comprising, in combination, an endless conveyer, means to guide it in a series of runs, carriers movably connected to the conveyer in series, each carrier having a guiding rib thereon; and devices for holding the carriers horizontal during their travel from one run to another, each comprising an arm, outside the path of the carrier with a box thereon offset within the path of the carrier for receiving the carrier rib and means for operating the same from the conveyer.
16. Apparatus of the class described comprising, in combination, an endless conveyer, means to guide it in a series of runs, carriers movably connected to the conveyer in series, each carrier having a guiding rib thereon; and devices for holding the carriers horizontal during their travel from one run to another, each comprising a box movable substantially vertically and in a straight path for receiving one carrier end and means permitting relative longitudinal movement of the carrier therein during travel of the box from one level to another.
17. Apparatus of the class described comprising, in combination, an endless conveyer, means to guide it in a series of runs, carriers movably connected to the conveyer in

- series, each carrier having a guiding rib thereon; and devices for holding the carriers horizontal during their travel from one run to another, each comprising a box 5
movable substantially vertically and in a straight path geared to travel vertically from one track to another while the carrier is travelling rotatively the same distance in sliding connection with the box.
- 10 18. In a machine of the class described, a series of carriers a stabilizer for the carriers and comprising a base, an arm thereon, a crank on the arm operated from the conveyor, a second arm with a carrier guiding 15 box thereon and connections between the crank and second arm for imparting vertically reciprocating motion to the latter.
19. In conveying apparatus comprising a series of carriers movable on different levels, 20 a carrier stabilizer comprising a base, an arm thereon, a box movably mounted on the arm and constructed and arranged to receive a carrier, and means to operate the box along a vertical path to stabilize the carrier 25 between levels.
20. In a conveying apparatus having carriers, a stabilizer, and a base, an arm on said base, a box carrying arm on the first arm, means on the base for imparting up 30 and down motion to the second arm to cause its box to have reciprocating engagement with a carrier while stabilizing the latter between levels.
21. In a conveying apparatus having carriers, a stabilizer, and a base, an arm on said base, a second box carrying arm on the first arm, means on the first arm for impart- 35
- ing both vertical and relative reciprocating movement to the box and carrier to cause the box to stabilize the latter between the 40 levels.
22. In conveying apparatus including a carrier, a stabilizer comprising a base, an arm thereon with a guide, a second box carrying arm with the box in the path of the 45 carrier and in engagement with the guide, a crank on the first arm creating vertical and relatively reciprocating motion between the box and the carrier to stabilize the latter between levels. 50
23. In conveying apparatus comprising a series of carriers moving along different levels, tracks of varying lengths, a short track guide on some of the tracks and a co-operating track guide member on each carrier having a longitudinally sliding engagement therewith; said cooperating track guides interengaging to prevent tipping movement of the carriers in either direction. 55
24. In conveying apparatus comprising a series of carriers, tracks therefor of unequal length, an outwardly turned flange on the short tracks, an inwardly turned flange on the carrier end for engagement therewith to stabilize the carrier. 60
25. In conveying apparatus comprising a series of carriers and having tracks therefor, short track guides on the inside of the track and beneath the carrier and a co-operating track guide member on the carrier end also beneath the carrier. 70

In testimony whereof, I have signed my name to this specification.

FORREST W. DIXON.
